UNITED STATES PATENT OFFICE

JOHN H. McCORMICK, OF CRESTON, IOWA

SOFT-COLLAR CLIP

Application filed November 17, 1930. Serial No. 496,181.

This invention relates to means for holding the points of soft collars in proper position for wear and to prevent wrinkling or undesirable flexing of said points, and the principal object is to provide an efficient means for this purpose which is inexpensive, easily applied, and invisible when in place.

A further object of the invention is to provide a wire clip of substantially inverted ⁵⁵ U-shape which is adapted to be mounted between the folds of a double or folded shirt collar and having sharp points on the ends of its arms adapted to penetrate the fabric at the point of the collar for holding these points in proper position.

Another object is to provide a device of the character described having such formation of the sharpened prongs for engaging the collar points that the prongs are easily engageable and removable and whereby the amount of penetration of the prongs is limited.

Another object of the invention is to provide such a device in which the cross bar is provided with a central seat or loop for engaging a collar button to prevent lateral movement of the clip in either direction.

With these and other objects in view my invention consists in the construction, arrangement and combination of the various devices, whereby the objects contemplated are attained, as hereinafter more fully described, pointed out in my claims, and illustrated in the accompanying drawing, in which:

Figure 1 is a front view illustrating one of my improved collar clips (shown by dotted lines) in position for use in connection with a shirt collar and necktie.

Figure 2 is an enlarged vertical section on the line 2—2 of Figure 1.

Figure 3 is an enlarged vertical section on the line 3—3 of Figure 1.

Figure 4 is an enlarged horizontal section on the line 4—4 of Figure 1.

Figure 5 is a perspective view of a clip constructed in accordance with my invention.

The use of relatively soft shirt collars, either of the attached or collar band type, which often are worn unstarched or with a

relatively small degree of stiffness, often causes annoyance to the user because of the tendency of the collar points to become wrinkled or to bend upwardly or forwardly or to be subject to other undesirable flexing.

In my present invention I have, therefore, provided a simple and efficient means for overcoming this tendency and for holding the collar points in their proper positions.

In the accompanying drawing there is shown a collar of the double or folded over type, in which the numeral 10a designates the band or inner fold and the numeral 10b designates the outer fold, the latter portion terminating in two spaced points 10c. In ⁶⁰ collars of this type the points such as 10c often are elongated considerably and this elongation increases the tendency toward wrinkling or flexing, particularly where little or no starch is employed in laundering ⁶⁵ 70 the collar.

In connection with the collar I have shown an ordinary four-in-hand necktie having a bight portion 12a enclosed between the two folds of the collar. The numeral 12b designates the knot of the necktie and the numeral 12c a flowing end thereof.

The clip forming the subject matter of my invention is composed of a single length of very light wire, such as piano wire, which ⁷⁵ 80 is bent to substantially inverted U-shape.

When so formed the clip includes a cross bar 14 and a pair of spaced downwardly projecting arms 16 and 18.

Preferably the wire is bent so as to form ⁸⁵ upwardly directed loops 20 and 22 at its ends and between the end portions of the cross bar and the upper portions of the respective arms 16 and 18. The wire preferably is bent rearwardly near the ends of the cross bar 14 so ⁹⁰ that the planes of the loops 20 and 22 are arranged at oblique angles to the vertical plane through the cross bar as most clearly shown in Figure 4. It is to be understood that in the use of the word "rearwardly" and kindred expressions, reference is had to the position occupied by the clip when it is in use.

At its center the cross bar 14 is formed with a concaved seat which is produced by ⁹⁵ ¹⁰⁰

forming a substantially semi-circular downward bend in the wire and this seat or loop is designated by the numeral 24.

5 The loop or seat 24 is adapted to engage behind the head and beneath the shank of a collar button such as 26 when the clip is in place, and the function of this engagement is to assist in centering the device and to prevent lateral movement in either direction 10 after it has been put in place.

15 Each arm 16 and 18 of the clip is formed at its free or lower end with a sharpened prong and these prongs are designated by the numerals 28 and 30 respectively. The 20 prongs 30 preferably are inclined downwardly and forwardly and are adapted to penetrate the fabric at the inner sides of the respective points 10c of the collar. To limit the amount of penetration of the prongs 28 and 30, the ends of the arms 16 and 18 are 25 formed with loops 32 and 34 respectively and the prongs are formed on and project from the upper ends of these loops. In other words, the material at the lower end of each 30 arm is first bent upwardly and then downwardly and outwardly, and sharpened to form the prong and the upper end of the recurved loop thus formed acts as a stop to limit the amount of penetration which is permitted as will clearly be understood from the 35 illustration in Figure 2.

40 The arms 16 and 18 may be formed at intermediate points with laterally directed bends or loops 36 and 38 respectively. It is 35 the function of these loops to provide convenient means for grasping or holding the relatively fine wire between the thumb and finger of the hand in adjusting the clip to its 45 position or removing it therefrom.

45 In placing the clip in position for use, the cross bar 14 is placed behind the knot 12b of the necktie and one of the prongs such for instance as 28 is caused to engage and penetrate the fabric on the rear side of one of the 50 points 10c. The device is pushed upwardly between the folds of the collar so that the central seat or loop 24 of the cross bar engages behind the head and beneath the shank of the collar button 26 and in such manner 55 that the upwardly directed loops 20 and 22 pass between the bight portion 12a of the tie and the outer fold 10b of the collar, at points near the fold line of the collar. Then the 60 prong such as 30 on the other arm of the clip is caused to engage and penetrate the fabric on the rear side of the other collar point 10c. This engagement may be effected by first moving the arm upwardly and then pulling it downwardly in such manner as to 65 cause the prong to penetrate the fabric.

65 It should be observed that the clip is made of relatively light spring wire which tends to hold its desired formation and which at the same time has sufficient flexibility to permit it to yield for accomplishing the de-

sired movement for adjusting and replacing it relative to the collar and necktie.

Furthermore, the arms of the clip are sufficiently stiff and strong to hold the points of the collar in the normal desired position and thus to prevent wrinkling or other undesirable flexing of these collar points. The clip also provides a support for the front part of the necktie and tends to assist in holding the knot snugly in place and to prevent slipping. 70 75

75 For removing the clip it is only necessary to first move one of the arms 16 or 18 upwardly a sufficient distance to permit its prong to disengage from the fabric, after which the clip may be readily manipulated in such ways as to remove the other prong from its engagement. It will be noted that the upwardly directed bends or loops 20 and 22 of the clip contribute to its flexibility or 80 85 ability to bend and assume the desired positions for adjusting and removing the clip.

85 Inasmuch as the central loop 24, by engaging the collar button, prevents lateral movement of the clip, it will be understood that under normal conditions it will always remain in the desired position until it is intentionally displaced. 90

90 It will further be noted that the provision for limiting the depth of penetration of the prongs 28 and 30 makes it very easy to remove the clip from the collar, and that there is no danger of tearing or otherwise injuring the fabric. 95

95 The prongs 28 and 30 preferably are in substantially the same planes as the double bends or loops 32 and 34 on which they are formed, and these planes are arranged substantially perpendicular to the general plane of the clip. In other words, the pointed prongs are 100 directed forwardly from and perpendicular to the common vertical plane of the two arms 16 and 18 on which they are formed. 105

105 The clip is very light and inconspicuous and when in use it is entirely concealed behind the necktie and the outer fold and points 110 of the collar.

110 The rearward bending of the upwardly directed loops 20 and 22 and the arms 16 and 18 formed thereon, causes the general shape of the clip to conform somewhat to the necessary curvature of the collar when it is in place, and also permits the clip to be placed under slight tension by the engagement of these loops between the portion 12a of the necktie and the outer fold 10b of the collar, with the simultaneous engagement of the central part of the cross bar 14 behind the knot of the tie and behind the head of the collar button. 115 120

120 All of these features contribute toward 125 making a simple and effective means for producing the desired results.

125 Some changes may be made in the construction and arrangement of the parts of my device without departing from the real

spirit and purpose of my invention, and it is my intention to cover by my claims, any modified forms of structure or use of mechanical equivalents, which may be reasonably included within their scope.

5 I claim as my invention:—

1. A collar clip adapted for use with a folded collar having spaced points, comprising a length of wire bent to substantially inverted **U**-shape to produce a cross bar and a pair of spaced depending arms, each arm being rebent upwardly at its lower end and then bent forwardly and sharpened to form a prong, each prong being adapted to penetrate the fabric at the rear side of one of the 10 collar points when the cross bar is arranged transversely between the folds at the front of the collar, for holding said points in place, the rebent portions at the lower ends of the 15 arms serving as stops to limit the penetration of said prongs whereby the clip may be placed under tension, said cross bar being formed at its center with a concaved upwardly opening seat adapted to engage a securing 20 means at the front of the collar, for preventing lateral movement of the clip.
2. A collar clip for use with a folded collar having a pair of spaced points and with a necktie worn therewith having a bight portion received in the fold of the collar and a knot located substantially between said 25 points; said clip comprising a cross bar and a pair of arms, one extending downwardly from each end of the cross bar, the cross bar adapted to be placed transversely behind the knot of the necktie and the arms being so positioned as to then lie behind the respective points of the collar, said arms being sharpened at their ends for penetrating 30 the fabric of the collar points, and means for limiting the depth of such penetration, said cross bar being formed near its ends with upwardly directed members adapted to engage in front of the bight of the necktie, whereby the cross bar serves to hold said 35 bight upwardly and the arms serve to hold the collar points down, said cross bar being formed at its center with an upwardly opening seat adapted to engage beneath a securing 40 member for the collar to prevent lateral shifting of the clip.

JOHN H. McCORMICK.
